UNITED STATES PATENT OFFICE.

GEORGE A. FARRER, OF BOONVILLE, CALIFORNIA.

COMMUTATOR ATTACHMENT FOR AUTOMOBILES.

1,357,158.

Specification of Letters Patent

Patented Oct. 26, 1920.

Application filed November 9, 1918. Serial No. 261,872.

To all whom it may concern:

Be it known that I, GEORGE A. FARRER, a citizen of the United States, residing at Boonville, in the county of Mendocino, State of California, have invented certain new and useful Improvements in Commutator Attachments for Automobiles; and I do hereby declare the following to be a full, clear, and exact description of the invention, such as will enable others skilled in the art to which it appertains to make and use the same.

The present invention relates to new and useful improvements in attachments for automobiles and more particularly directed to the provision of an improved commutator mounting for that type of automobile engine structure wherein normally the commutator is positioned in the lower portion 15 of the forward end of the crank casing, this arrangement being found in automobile engines of the Ford or similar types.

With a commutator positioned at the lower portion of the forward end of the crank casing, the sparking wires leading from the commutator are liable to be engaged by the belt of the radiator fan, and consequently damaged. Also grease from the engine structure finds its way into the commutator, necessitating a frequent cleaning thereof, and impairing the efficient operation of the commutator.

It is therefore primarily the object of the present invention to provide an arrangement for so positioning the commutator that the wires leading therefrom are not subject to engagement by any movable parts of the engine structure, and wherein access of oil to the commutator is prevented.

It is more particularly the object to provide an arrangement wherein the ordinary commutator of an engine structure and the ordinary drive means therefor may be utilized without any substantial modification of such parts and wherein interposed means is provided for driving the commutator by its normal drive means in a position remote therefrom.

With the above and other objects and advantages in view, the invention resides more particularly in the novel combination, formation and arrangement of parts hereinafter described and particularly pointed out in the appended claims.

In the accompanying drawings:

Figure 1 is a front elevational view of the improved commutator device associated with a conventional engine structure.

Fig. 2 is a side elevational view thereof.

Fig. 3 is a longitudinal sectional view 60 through the commutator and shaft housing.

Fig. 4 is a detail sectional view on the line 4—4 of Fig. 2.

Fig. 5 is a plan view of the commutator and timer controlling mechanism.

Fig. 6 is a detail section on the line 6—6 of Fig. 1.

Referring now more particularly to the accompanying drawings, 5 designates the front portion of the crank casing of an engine of the Ford type, and 6 designates the ordinary cam shaft which extends through the housing into the usual cup-shaped rotatable commutator casing 7 carrying binding posts 8 corresponding in number to the cylinders of the engines and having contact members or points 9 at its inner periphery engagable by the usual spring urged commutator roller 10 rotatable within the commutator casing.

In the application of the present invention, the commutator casing 7 and the roller 10 and its mountings are removed from the cam shaft 6, and fixed on the end of the cam shaft and held by nut 11 is a beveled gear 12 meshing with a beveled gear 13 carried on the lower end of a shaft 14 journaled in a sleeve housing 15. The latter has its lower end merged into a gear casing 16 which is adapted to fit against 90 the crank casing 5 in the manner of the removed commutation casing and which is secured in place by a pair of arms 17 extending divergently downwardly therefrom and bolted at 18, to the crank casing. The 95 housing and shaft extend upwardly and are inclined toward one side of the engine structure and at the upper end of the housing is formed a seating plate 19 having an upturned peripheral flange 20 within which 100 is seated the mouth of the commutator casing 7 and the shaft 14 is extended into the commutator casing thus positioned and has fixed thereon the commutator roller 10. For holding the commutator casing in place, an 105 upright post 21 carried by a radial extension of the plate 19 has secured thereto by the bolt 22, one end of a spring finger 23 having its other end engaged against the outer portion of the commutator casing to hold it 110

within the shallow cup formed by the plate 19 and its flange 20.

Journalized in the widened base of the post 21 is a rock shaft 24 having a crank arm 25 at one end to which is secured a rod 26 extending to the usual control means for timing the action of the commutator. At the other end of the rock shaft is provided an upstanding crank arm having a ball-and-socket connection 27 at its upper end with a link 28 connected with the commutator casing by a depending finger 29 engaged in a socket sleeve 30 on the commutator whereby the casing may be correspondingly rocked to advance or retard the sparking operation.

An exceedingly simple arrangement has thus been provided whereby the commutator of an engine of the class described may be placed in such position as to prevent access 20 of oil thereto from the engine casing. The wires 31 extending from the binding posts 8 of the commutator casing are preferably strung along the usual top radiator rod and thus are afforded an efficient support in 25 their passage from the hood of the automobile, and are prevented from possible damaging contact with the fan structure or any movable parts of the engine. The entire device may be readily applied to an automobile structure, and provides for a most highly 30 efficient commutator operation.

What is claimed is:

1. In a commutator, the combination with 35 a rotary shaft, a seating plate surrounding the same and having an annular upstanding flange and a post, and a roller carried by said shaft; of a casing rotatably adjustable on the plate within its flange and carrying

points with which said roller comes into 40 successive contact, a spring finger mounted on the upper end of said post and bearing downward upon said casing, a rock shaft journalized through said post and having two cranks, a rod connected with one crank and leading to a distant point, and a link having universal connections at its extremities with the other crank and with the casing for adjusting the position of the latter as described. 50

2. In a commutator, the combination with a substantially upright shaft, a tubular housing surrounding the same and having a seating plate at its upper end, the plate provided with an annular upstanding flange 55 and a radial finger carrying a post, a roller carried by the upper end of said shaft, and means for rotating the shaft from its lower end; of a casing rotatably mounted on the plate within its flange and carrying points 60 with which said roller comes into successive contact, a spring finger mounted at one end on the upper end of said post and bearing downward at its other end upon said casing, a rock shaft journalized through the base of 65 said post and having cranks at its extremities, a rod connected with one crank and leading to a point within reach of the operator, and a link having universal connections at its extremities with the other crank 70 and with the casing for adjusting the position of the latter, as described.

In testimony whereof, I affix my signature, in the presence of two witnesses.

GEORGE A. FARRER.
